[57] CLAIM

The ornamental design for an automatic self-watering plant pot, as shown and described.

DESCRIPTION

FIG. 1 is a front elevational view of the self-watering plant pot showing my new design;

FIG. 2 is a top plan view therof, and the bottom of the self-watering plant pot is flat and forms no part of the claimed design;

FIG. 3 is a rear elevational view; and,

FIG. 4 is a left side elevational view therof.
